CLAIM

The ornamental design for an audio input/output device, as shown and described.

DESCRIPTION

FIG. 1 is a perspective view of an audio input/output device; FIG. 2 is another perspective view of the audio input/output device of FIG. 1;

FIG. 3 is a front view of the audio input/output device of FIG. 1;

FIG. 4 is a back view of the audio input/output device of FIG. 1;

FIG. 5 is a left-side view of the audio input/output device of FIG. 1, the right-side view of the audio input/output device being a mirror image of the left-side;

FIG. 6 is a top view of the audio input/output device of FIG. 1; and,

FIG. 7 is a bottom view of the audio input/output device of FIG. 1.

The broken lines are directed to unclaimed portions of the audio input/output device and form no part of the claimed design.

1 Claim, 6 Drawing Sheets

Related U.S. Application Data

continuation of application No. 29/503,695, filed on Sep. 29, 2014, now Pat. No. Des. 744,541.
